UNITED STATES PATENT OFFICE.

MOODY BOYD, OF LOUISVILLE, KENTUCKY.

REFRIGERATING-MACHINE.

1,207,130.

Specification of Letters Patent.

Patented Dec. 5, 1916.

Application filed January 13, 1915. Serial No. 2,020.

To all whom it may concern:

Be it known that I, Moody Boyd, a citizen of the United States, residing at Louisville, in the county of Jefferson and State of Kentucky, have invented a new and useful Refrigerating-Machine, of which the following is a specification.

The present invention relates to improvements in a refrigerating machine, and more especially to a type of machine adapted to be used for domestic purposes and used in connection with a cold storage receptacle so as to dispense with the use of ice and the continual replenishing thereof, one object of the invention, being the provision of an ammonia process, apparatus, in which the usual pressure or vacuum pump is dispensed with, the desired pressure and vacuum being produced by heat and a cooling action, and a consequent expansion and contraction of the gas.

A further object of the present invention, is the provision of a simple and comparatively cheap apparatus of this character which may be readily installed in residences and connected to a storage compartment so that the same will be properly cooled to produce the desired refrigeration.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a diagrammatic view of the complete apparatus embodying the present invention. Fig. 2 is a section taken on line 2—2 of Fig. 1.

In carrying the present invention into operation, there is a supporting structure 1 to which is properly supported by any desired means, preferably so as to be swung into and out of position, the receptacles or tanks 2 and 3, the same being preferably cylindrical tanks for containing aqua ammonia. Disposed below the respective tanks 2 and 3 are the heating devices 4 and 4' which are indicative of any form of device for producing the necessary temperature in the tanks 2 and 3 to drive the ammonia gas from the same.

Leading from the respective tanks 2 and

3 are the gas conducting pipes 5 and 5', respectively, provided with the manually controlled valves 6 and 6', the pipes 5 and 5' being connected to the coil 8 with a gage 7 interposed.

The coil 8 is disposed within the tank 9, which is provided with water circulating valves 10 and 10' so that water may be circulated through the tank 9 to condense the ammonia gas fed from either one of the respective receptacles or tanks 2 and 3.

An automatic relief valve 11 is provided in the pipe 12 which is led from the coil 8, to retain the ammonia in the coil until a predetermined pressure is attained while the reservoir or retaining tank 13 is in communication with the pipe 12 to receive the ammonia from the coil 8 when released by the valve 11.

A pipe 14 is led from the storage tank 13 controlled by the manual valve 15, there being also connected to the pipe 14 a reserve ammonia holding tank 16, so that ammonia from the tanks 13 and 16 may be directed through the conduit 17 under pressure and in liquid form to the expansion valve 18 which is disposed within the storage receptacle R. The storage receptacle R may be taken indicative of any receptacle adapted to receive provisions or other material to be refrigerated. The valve 18 is a manually controlled valve adjusted to permit the ammonia to expand to a gaseous state directly into the coil 20 and thus increase or decrease refrigeration as the coil is disposed within the brine tank 21. A return pipe 22 is led from the coil 20 to the branches 23 and 23', which are in communication through the respective pipes 24 and 24' with the tanks 2 and 3. Manually controlled valves 25 and 25' are disposed at the junction of the pipes 23 and 24, and 23' and 24' so that the respective tanks 2 and 3 may be alternately isolated.

In order to provide a means for cooling the respective tanks 2 and 3, and thus assisting in the creation of a vacuum therein, the purpose of which will later appear, there is disposed for swinging movement to incase either one of the tanks as desired, a water holding trough 26 as clearly illustrated in Fig. 2. This trough can be arranged to slide and swing upon a rod 26' supported adjacent the tanks 2 and 3 and within the structure 1.

From the foregoing description, the oper-

ation of the present machine is readily understood, but briefly stated it is as follows:—Assuming that the tank 2 is filled with aqua ammonia, the valves 25 and 6' 5 being closed so as to isolate the tank 3 from the apparatus, the burner 4 is ignited so as to heat the tank 2 and consequently drive the gas through the valve controlled pipe 5, the valve 6 therein having been opened. 10 The gas will then pass into the coil 8 where it is condensed by the water in tank 9 and after a sufficient pressure has been accumulated therein, the same is automatically released by the valve 11 to pipe 12 into the 15 storage tank 13, the same having been cooled and then passed through the pipes 14 and 17 to the expansion valve 18 and finally into the coil 20 where the desired cooling action is had upon the brine within the tank 21. 20 The gas flows back through the pipe 22 and the branches 23' and 24' into the tank 3, which may have been submerged in the trough 26 so as to cool the same and thus cause the gas contained therein to contract 25 and thus produce the desired vacuum effect to produce the desired circulation. Thus the tank 2 produces the desired pressure to force the ammonia through the system while the tank 3 acts as a vacuum producing means 30 to assist in the circulation thereof. After the ammonia has been accumulated in the tank 3, the burner 4 is cut out and the trough 26 placed around the tank 2, or the tank 2 permitted to cool slowly. While the 35 tank 2 is acting as an absorber the valve 25 is open and the valve 23' closed, and the circulation is through the pipes 22, 23 and 24 into the tank 2.

It will thus be seen with the present apparatus for residences and grocers, butchers and the like, that the use of ice is dispensed with, and that an ammonia refrigerating apparatus without the usual compressor or 40 vacuum pump is provided, the desired circulation being produced by the pressure of the gas itself and the absorption thereof.

It will also be noted that after the machine is in operation, it will not be necessary to cool the tanks 2 or 3 with water in the trough 26, except in an emergency, nor 50 will it be necessary to stop refrigeration while the gas is being generated. When generating the gas in tank 2, the tank 3 will be the absorber, this action alternating. The tank 13 is designed to hold sufficient 55 ammonia for one or more day's refrigeration and will thus permit the natural cooling of the tanks 2 and 3 without the use of running water.

The reserve tank 16 is of such a size as to 60 hold sufficient ammonia to operate the machine for several hours at night, the valve 15 being closed at this time and the apparatus not using as much ammonia for the reason that the doors to the storage chamber 65 R are closed.

What is claimed is:

A refrigerating apparatus including a supporting structure, two tanks suspended therefrom and adapted to be swung into 70 and out of position, a heater below each of the tanks, a cooling trough shiftable to position to receive either of the tanks, said trough being mounted to swing relative to the tanks, a refrigerating coil, a pipe leading from said coil to the two tanks, valves for controlling the flow of gas from said pipe to the respective tanks, a condensing coil, a valved pipe leading from each tank to the condensing coil, a relief valve adjacent the condenser, liquid storage tanks, a pipe extending from the relief valve to the tanks and from said tanks to the refrigerating coil, and an expansion valve interposed 75 between said pipe and the refrigerating coil. 80

In testimony that I claim the foregoing as my own, I have hereto affixed my signature in the presence of two witnesses.

MOODY BOYD.
